UNITED STATES PATENT OFFICE.

MARSHALL HENRY PEARSON, OF LEICESTER, ENGLAND, ASSIGNOR TO THE UNITED SHOE MACHINERY COMPANY, OF PATERSON, NEW JERSEY.

STITCH-SEPARATING MECHANISM FOR SEWING-MACHINES.

SPECIFICATION forming part of Letters Patent No. 658,996, dated October 2, 1900.

Application filed May 3, 1900. Serial No. 15,374. (No model.)

To all whom it may concern:

Be it known that I, MARSHALL HENRY PEARSON, a subject of Great Britain, residing at Union Works, Belgrave road, Leicester, in the county of Leicester, England, have invented certain new and useful Improvements in Sewing-Machines; and I do hereby declare the following to be a full, clear, and exact description of the invention, such as will enable others skilled in the art to which it appertains to make and use the same.

The present invention relates to an improvement in sewing-machines, and more particularly to an improvement in sewing-machines embodying stitch-forming mechanism and stitch setting or pricking-up devices. In so far as I am advised of the prior art, in such sewing-machines the stitch has heretofore been tightened by the stitch-forming mechanism and thereafter the stitch setting or pricking-up devices engaged either one or both sides of the stitch just completed and pressed and shaped it and then retreated from the work, and the stitch-forming mechanism operated to form the next stitch. The operation of the stitch setting or pricking-up devices upon the stitch compressed the leather and incidentally loosened to some degree the stitch. Furthermore, the work was fed by the needle, by the awl, or by a feed-surface, and when stitch setting or pricking-up devices were added thereto, increasing the number of parts operating directly on the work, difficulty was encountered, owing to the small space within which the operations of such parts were necessarily confined.

The object of the present invention is to reorganize and improve sewing-machines of this class, so as to remove the defects above noted.

According to my invention after the forming and preliminary tightening of a stitch and the application thereto of stitch setting or pricking-up devices and their withdrawal from the stitch the thread or threads are given a further pull to again tighten the stitch, so as to make the seam perfectly tight, and I believe I am the first to apply a stitch-tightening pull to the thread or threads after a preliminary stitch-setting operation of the stitch setting or pricking-up devices.

Furthermore, according to my invention I feed the work with the stitch setting or pricking-up devices, and I believe I am the first to feed the work by such devices. I have also improved sewing-machines of this class in other respects, hereinafter described.

To the above ends the present invention consists in the devices and combinations of devices hereinafter described and claimed.

In the accompanying drawings, illustrating the preferred form of my invention, Figures 1^a and 1^b are views which taken together show a sectional side elevation, Fig. 2 is a plan, Fig. 3 is a rear elevation with the pulley removed, Fig. 4 is a partial sectional rear elevation, Fig. 5 is a partial sectional front elevation, and Fig. 6 is a partial front elevation, of my machine. Fig. 7 is a top plan, Fig. 8 is a side elevation, and Fig. 9 is an end elevation, of the shuttle. Fig. 10 is an isometric view of the shuttle-carrier. Fig. 11 is an isometric view of the shuttle-carrier joint-block. Figs. 12 and 13 illustrate certain details of construction hereinafter described. Figs. 14, 15, and 16 are enlarged side elevation, bottom plan, and end elevation, respectively, of the top pricking-up tool. Fig. 17 is a transverse section through the shuttle-carrier at line a b, Fig. 10, showing the joint-block in operative position therein. Figs. 18, 19, and 20 are enlarged plan, side elevation, and end elevation, respectively, of the bottom pricking-up tool and its carrier; and Figs. 21, 22, and 23 are enlarged side elevation, plan, and end elevation, respectively, of the tool-carrier slide.

The frame A supports the main shaft B in suitable bearings therein. The pulley C constitutes a belt-wheel, by which the machine is driven, as well as a balance-wheel. A series of cams D, E, F, and G are provided with a series of cam paths or grooves or cam-surfaces by which the operative parts of the machine are driven.

In the machine of the drawings the needle 1 coöperates with the shuttle 2 to form the stitch. The needle is mounted on the needle-bar 1^a, which is arranged to reciprocate in bearings 1^b 1^c in the frame A of the machine. The needle-bar is actuated by a link 1^d, pivoted at 1^e to a block secured to the needle-

bar 1^a and at 1^f to a pin secured in the end of a lever 1^g, which lever is mounted upon the stud 1^h, supported by the frame of the machine. The link 1^d is actuated by a connecting-rod 1ⁱ, pivoted to it at 1^j and to the bell-crank needle-cam lever 1^k at 1^l. One arm of the lever 1^k carries a cam-roll 1^m, which is received by the cam-groove 1ⁿ in the cam G, secured to the main shaft B of the machine.

10 The above-described arrangement is such that the rotation of the cam-shaft imparts oscillating movements to the needle-cam lever 1^k, which in turn reciprocates the connecting-rod 1ⁱ and actuates the needle-bar 1^a through the link 1^d.

The shuttle 2 is an elongated substantially cylindrically-shaped hollow body provided at its rear end with a hinged closure 2^a, which is adapted to be opened for the insertion of 20 the shuttle-bobbin 2^b. The upper part of the shuttle is provided with a flange 2^c, which extends forwardly beyond the end of the shuttle and is provided with a sharp edge adapted to engage the loop of thread drawn 25 down by the needle and to open the same. One side of the front end of the flange 2^c of the shuttle is cutaway, as at 2^d, through which recess after the shuttle has been moved forward to open the loop of thread drawn down 30 by the needle the spreader-hook may pass to engage and open the loop of thread for the shuttle to pass through. The shuttle is provided with a tension-spring 2^e, which may be adjusted by means of the tension-adjusting 35 screw 2^f. The shuttle-thread emerges from the shuttle through the slot 2^g in its side, passes up through the slot 2^h in the flange of the upper edge of the shuttle, down on the other side underneath the tension-spring, 40 thence through the eye 2ⁱ, from which it leads to the work. The shuttle is operated by a shuttle-carrier 3, which consists of two parallel bars 3^a, a slotted block 3^b, which unites the two parallel bars 3^a at one end, and the 45 perforated block 3^c, which unites the parallel bars at the opposite end. The block 3^b is slotted at 3^d to receive the forwardly-projected end of the flange 2^c of the shuttle and the spreader-hook, hereinafter described.

50 The perforated block 3^c is provided with a cylindrical hole 3^e, which receives the joint-block 3^f, (see Figs. 11 and 17,) within which said joint-block fits and may be oscillated. The joint-block is provided with a hole 3^g, which is adapted to receive the end of the 55 lever which operates the carrier to impart reciprocations thereto. The perforated block 3^c is also provided with a hole 3^h, through which said operating-lever may pass. The 60 shuttle-carrier is reciprocated by means of the shuttle-cam lever 3ⁱ, (shown in dotted lines in Fig. 1^b), which is pivoted at 3^j to the frame of the machine and carries the cam-roll 3^k, which is engaged by the cam-groove 3^l in 65 the cam D, mounted on the main shaft B of the machine. The above-described arrangement is such that the cam-groove 3^l through

the shuttle-cam lever 3ⁱ imparts longitudinal reciprocations to the shuttle-carrier 3, which in turn reciprocates the shuttle in the shuttle-race 3^m.

In connection with the shuttle I employ a spreader-hook 4, which after the point of the shuttle has entered the loop of thread drawn down by the needle engages such loop of thread and opens it to permit the shuttle to pass through. The spreader consists of a hook mounted upon the end of spreader-arm 4^a, to which it is adjustably secured by means of the screws 4^b. The spreader-arm 4^a is projected forwardly from a sleeve 4^c, mounted upon a stud 4^d, fixedly supported upon the frame of the machine. Rearwardly projected from the sleeve 4^c is an arm 4^e, which carries upon its extremity a cam-roll 4^f, which is received within the spreader-cam groove 4^g of the cam G, mounted upon the main shaft B of the machine. The spreader-cam groove 4^g and the shuttle-cam groove 3ⁱ are so timed with relation to each other that the hook of the spreader engages the needle-thread after the point of the shuttle has engaged it and separated it from the needle, and then it pulls down the needle-thread for the shuttle to pass through, after which the shuttle is moved to 95 pass through said loop.

The presser-bar 5, provided with a presser-foot, (not shown,) is mounted in bearings 5^a 5^b in the frame of the machine and adapted to reciprocate therein. The presser-bar is provided with a spline 5^c, which is projected outwardly through the groove 5^d in the bearing 5^a. A spring 5^e encircles the presser-bar and normally presses it downward to engage the work. Means are provided for locking the presser-bar in its position in engagement with the work and for lifting the presser-bar during the feed of the work. Loosely mounted upon the upper end of the presser-bar is a sleeve 5^f, through which the bar moves with an easy sliding fit. This sleeve 5^f is provided with a hole therethrough perpendicular to the axis of the presser-bar, and said hole receives a stud 5^g, which is cut away to receive the presser-bar, as shown in detail in Fig. 13. 115 The stud 5^g is provided with an arm 5^h, which is projected into a jaw 5ⁱ in the end of the lever 5^j, pivoted on the stud 5^g, supported on the frame of the machine. The stud 5^g is secured in place by the set-screw 5^l. The lever 5^j is pivotally connected at its opposite end at 5^m with a connecting-rod 5ⁿ, by which said lever 5^j is operated. The connecting-rod is pivoted at 5° to the bell-crank lever 5^p, pivoted at 5^q to the frame of the machine. 125 The other end of the bell-crank lever 5^p carries the cam-roll 5^r, which engages the presser-cam groove 5^s on the cam E, mounted on the main shaft B of the machine. The presser-cam groove 5^s, through the medium of the 130 bell-crank lever 5^p, the connecting-rod 5ⁿ, and the lever 5^j, operates, after the presser-bar has been forced down by the spring 5^e into contact with the material, to tip the stud

5⁵ to clamp it against the presser-bar to hold said bar in its position. A spring 5^t, mounted upon the presser-bar above the sleeve 5^f, bears at its upper end against the projection 5^u on the frame of the machine and normally operates to press the sleeve downward. The presser-cam groove 5^s and the above-described mechanism are arranged to hold the presser-bar against the material after it has 10 been forced down by the spring 5^e into engagement with the work and thereafter to lift the presser-bar while the material is fed. Then after the feed is completed the presser-bar is again permitted to be pressed downward by its spring 5^e.

The take-up 6 consists of a thread-truck 6^a, mounted on a take-up arm 6^b, secured to a rock-shaft 6^c, carried in suitable bearings 6^d and 6^e in the frame A of the machine. The 20 take-up is supported in front of the head of the machine and actuated by suitable mechanism to exert a pull upon the needle-thread after the shuttle has passed through it to interlock the needle and shuttle threads, to 25 draw the thread into the material to form the stitch, and to effect a preliminary tightening thereof, and subsequently after the stitch setting or pricking-up devices have first engaged and released the stitch thus formed in 30 the manner hereinafter described the take-up (the needle and shuttle contributing to the result) makes a further pulling stroke on the thread to tighten the stitch and to draw it to its final position in the materials around 35 the compressed materials. The mechanism for actuating the take-up consists of the arm 5^f, secured to the rock-shaft 6^c, to which arm the one end of the connecting-rod 6^g is attached, the other end of the connecting-rod 40 being attached to the take-up cam-lever 6^h, which is pivoted at 6ⁱ to the frame A of the machine. The lever 6^h carries the cam-roll 6^j, which is operated by the cam-groove 6^k of the cam G, mounted on the main shaft B of 45 the machine, the above arrangement and its operative relation to the stitch setting or pricking-up devices, hereinafter described, being such as to cause the take-up to exert a pull upon the thread after the shuttle has 50 passed through the loop of needle-thread, to effect a preliminary tightening of the stitch, and after the stitch setting or pricking-up devices have engaged the stitch and compressed it and the intervening materials and 55 have released themselves therefrom to cause it to exert a further pull on the thread to give the thread its final stitch-tightening pull to tighten the stitch in its final position in the seam.

60 While I have thus described the specific form of stitch-forming mechanism illustrated in the drawings, my invention is by no means specifically limited thereto.

65 My invention is capable of embodiment in a chain-stitch sewing-machine, as well as in a lock-stitch machine, and it is immaterial to my invention, considered in its broadest as-

pect, whether or not the several pulls upon the thread before and after the stitch setting or pricking-up devices have performed their 70 function is exerted by the take-up, needle, and shuttle, or by either one alone, as my invention contemplates, broadly, coöperating mechanism for forming stitches arranged to exert stitch-tightening pulls upon the thread 75 before and after the operation of the stitch setting or pricking-up devices.

The stitch setting or pricking-up devices consist in the machine of the drawings of two oppositely-disposed coöperating stitch-engaging tools, which after the formation of a stitch by the stitch-forming mechanism engage the oppositely-disposed crowns of a stitch and set or prick up the stitch, thereby imparting to the stitches a uniform and pleasing 85 appearance. Moreover the lower tool pushes in the grain of the leather, which has been pushed out by the needle, and both of them compress and solidify the materials. After this stitch-setting operation of the two tools 90 they are simultaneously released, and while the presser-foot is still holding the work firm the final pull, above described, is given to the thread by the further movement of the needle and take-up upward and of the shuttle forward, the action being to again pull on the threads and to tighten them after the leather or other material has been compressed. This 95 pulling upon the threads draws them home and holds the materials firmly together. 100 These two tools then again drop onto the stitches, the presser-foot rises, and the leather is moved back by a simultaneously rearward movement of the top and bottom tools to the extent of the length of stitch desired, and 105 these tools hold the stitch firmly compressed until the needle has again descended and risen and pulled another stitch into position.

Two sets or groups of mechanism operate the stitch setting or pricking up tools, the 110 one for moving them toward and from the work comprising what may be termed "mechanism for actuating the stitch setting or pricking up tools to set or prick up the stitches," and the other for moving them forward and 115 back for feeding the work comprising what may be termed "mechanism for actuating the stitch setting or pricking-up tools to feed the work." The sets or groups of mechanism taken together comprise the stitch setting or 120 pricking-up actuating mechanism.

The stitch setting or pricking-up tools operate on the top and bottom of the work, and for convenience I will herein designate them, respectively, the "top" and "bottom" tools. 125

I will first describe the two tools and their respective supports. I will then describe the mechanism for actuating the tools to set or prick up the stitch, and will finally describe the mechanism for actuating the tools to feed 130 the work and the coöperative relation between the two groups of mechanism and the stitch-forming mechanism, hereinbefore described. The top tool 7 consists of a piece of steel hav-

ing a downwardly-extending work-engaging end, which is grooved transversely to the line of the seam, the groove being shaped to conform to the shape of the stitch. (See Figs. 5 14 and 16.) This tool is adjustably secured to the lower end of the pricker-bar 7^a by a set-screw 7^b. The pricker-bar is mounted in bearings 7^c and 7^d, secured to or integral with a slide 7^e, mounted upon a guide 7^f, secured 10 to the front of the frame A of the machine. The pricker-bar 7^a is provided with an outwardly-projected spline 7^g, engaging a groove 7^h in the bearing 7^d, by which the pricker-bar 7^a is held from rotation. The bottom tool 8 15 consists of a short stud or projection mounted on the slide 8^a, and which tool has a stitch-engaging end grooved transversely to the line of the seam and shaped to conform to the shape of the stitch. The tool 8 is secured to the 20 slide 8^a in the following manner: The tool is mounted upon a tool-carrier 8^b, which extends longitudinally of the slide, lying in a groove in the upper face thereof, and is held from longitudinal movement in said slide by the 25 screw 8^c. The slide 8^a is supported in bearings in the frame of the machine, extending over the shuttle-race, the slide 8^a and tool-carrier 8^b being provided with suitable holes 8^d and 8^e, respectively, to permit the needle 30 1 to descend therethrough. The bottom tool 8 extends up through a slot in the needle-plate 10, carried by the cover-plate 10^a of the machine.

The above-described arrangement is such 35 that the two stitch setting or pricking-up tools are supported upon opposite sides of the work in position to engage the stitch after the needle has retreated from the work, and which are capable of adjustment with relation to 40 each other, so as to bring them into accurate opposition.

The mechanism for actuating the top tool to set or prick up the stitch and to lift it when required is as follows: The tool-bar 7^a is surrounded by a coiled spring 7ⁱ, which acts normally in a direction to force the tool-bar 7^a down in contact with the work. The tool-bar 7^a is provided above the bearing 7^d with a bar-clamp lifting and locking device similar in all 50 respects to the presser-bar lifting and locking device, hereinbefore described, and which therefore needs no repeated description at this point. The device for actuating the clamp of the tool-bar 7^a is, however, different 55 from that which operates the clamp 5^h, and in the following respects: that the end of the clamp 7^j rests upon a lug or stud which when the stud is raised operates to operate the clamp to engage the tool-bar and to raise 60 it therewith. Upon the descent of the lug or stud the clamp is released and the tool-bar drops and forces the tool against the stitch to set it. The lug or stud above referred to is the stud 7^k, mounted upon the 65 end of the arm 7^l of the rock-shaft 7^m, mounted in a bearing in the frame A of the machine. The rock-shaft 7^m is provided with

another arm 7ⁿ, to the end of which is pivoted the connecting-rod 7°, extending down to the bell-crank lever 7^p, to one of the arms of 7° which it is secured. The bell-crank lever 7^p is secured to the rock-shaft 7^q, supported in bearings in the frame of the machine and operated by means of the cam-lever 7^r, pivoted at 7^s to the frame of the machine. The 75 cam-lever 7^r carries a cam-roll 7^t upon one end, which engages the operating-cam surface 7^u of the cam F, mounted on the main shaft B of the machine. The other end of the lever 7^r carries a block, pivotally secured 80 thereto, which engages a fork in one of the arms of the bell-crank lever 7^p. By this means the bell-crank lever 7^p is actuated by the cam-lever 7^r. The mechanism for actuating the bottom tool to set or prick up the 85 stitch and to lower it when required consists of an arm 8^d, mounted on the rock-shaft 7^q, which arm carries on its upper end the roll 8^e, upon which roll rests one end of the slide 8^a. The above-described arrangement is such 90 that the cam 7^u actuates the two tools simultaneously from opposite directions, the top tool 7 through the bell-crank lever 7^p, the connecting-rod 7°, the rock-shaft 7^m, the stud 7^k, the clamp-lever 7^j, the tool-bar 7^a, and 95 the bottom tool through the arm 8^d and roll 8^e, which latter directly supports the lower tool 8.

The mechanism for actuating the stitch setting or pricking-up tools to feed the work 100 is as follows: The slides 8^a and 7^e are actuated from the feed rock-shaft 9, which carries two arms, which are connected to the two slides, respectively, the arm 9^a, engaging the slide 7^e and actuating it and the arm 9^b being 105 connected to the slide 8^a (by a universal joint) and actuating it. The points of application of the arms 9^a and 9^b with the slides 7^e and 8^a are equidistant from the rock-shaft 9, so that the two slides are moved in accurate 110 unison. The rock-shaft 9 is provided with an arm 9^c, which carries on its end a block 9^d, which is engaged and actuated by a groove 9^e in a block 9^f, revolvably mounted in the arm 9^g, secured to the rock-shaft 9^h, to which 115 rock-shaft the arm 9ⁱ is secured, which arm on its end carries a cam-roll 9^j, which engages the cam-groove 9^k of the cam E, mounted on the main shaft B of the machine. Oscillations imparted to the rock-shaft 9^h by the 120 cam-groove 9^k are imparted to the rock-shaft 9 through the medium of the arm 9^g, groove 9^e, block 9^d, and arm 9^c. The groove 9^e in the block 9^f is circularly curved, with a radius at the center line equal to the distance of the center line of the groove from the center of the rock-shaft 9^h. The arm 9^g is provided with a segment 9^l, and the block 9^f is provided with an arm 9^m, which is projected from the block over the segment 125 9^l and provided at its end with a spring-clip 9ⁿ, adapted to engage the segment 9^l. When the block 9^f is adjusted so that the center of curvature of the groove 9^e coin-

cides with the center of the rock-shaft 9^b, oscillations of the rock-shaft 9^b will impart no motion to the rock-shaft 9; but when the block 9^f is so adjusted by moving the arm 9^m 5 along the segment 9^l that the center of curvature of the groove 9^e does not coincide with the center line of the rock-shaft 9^b then oscillations of the rock-shaft 9^b will impart corresponding oscillations to the rock-shaft 9, 10 and consequently corresponding reciprocations to the slides 7^e and 8^a, respectively. This device comprises a feed-adjuster, by means of which the length of the strokes of the slides 7^e and 8^a are adjusted to the desired 15 length of stitch. Thus it will be seen that the mechanism for actuating the stitch setting or pricking-up tools to feed the work is entirely independent of the mechanism for actuating the stitch setting or pricking-up 20 tools to set or prick up a stitch and that the length of the feed and the corresponding length of stitch is regulable.

The cam 7^u for actuating the stitch setting or pricking-up tools to set or prick up the 25 stitch is so timed with relation to the timing of the cam-groove 9^k, which operates the mechanism for actuating the stitch setting or pricking-up tools to feed the work and with relation to the cam-groove 6^k for operating 30 the take-up 6, the cam 1ⁿ for actuating the needle, the cam 3^l for actuating the shuttle, the cam 4^g for actuating the spreader, and the cam 5^s for actuating the presser, that the operation of the stitch setting or pricking-up 35 tools, the needle, the take-up, the shuttle, the spreader, and the presser occur as follows: The needle descends and carries a loop of thread down through the material, the shuttle advances and enters the loop of thread so 40 drawn down, the spreader engages the loop and opens it for the shuttle to pass through, the shuttle passes through, the needle retreats, the take-up rises, the shuttle advances and the threads are interlocked, and the stitch 45 is formed and preliminarily tightened around the material. Then the stitch setting or pricking-up tools engage the stitch thus formed from opposite sides and simultaneously compress and form it and compress and solidify 50 the leather or other material, the stitch setting or pricking-up tools are simultaneously released and the needle, shuttle, and take-up exert a further pull upon the threads to tighten them about the compressed and solidified material. Then the stitch setting or 55 pricking-up tools again drop onto the stitches, the presser-foot is released, and the leather or other materials is moved back by a simultaneous rearward movement of the top and bottom tools to the extent of the length of the 60 stitch desired, and these tools hold the stitch firmly compressed until the needle has again descended and risen and pulled another stitch into position, thereby preventing the stitch 65 from loosening itself until the next stitch is formed, when it is held thereby in its tightened position, whereupon the stitch setting or

pricking-up tools recede from the work, move forward to positions above and below the stitch just formed, and again drop on the stitch 70 and compress and shape it to the desired form, the operations thus described being successively repeated in the formation of a seam of stitches. It will be noted in this connection that the bottom stitch setting or pricking-up tool pushes in the grain of the leather which has been pushed out by the needle and compresses the leather under the stitches. The motions of the presser-bar carrying the presser-foot, which engages and holds the 80 material, are simply rising and falling motions, the foot being raised during the feeding of the work and dropped and locked to hold the work firmly in position during the time the needle and the other stitch-forming devices 85 are operated to form the stitch and raised during the time the stitch setting or pricking-up tools are feeding the work.

I have not shown herein in detail the form of the several cam paths, grooves, and surfaces, hereinbefore referred to, for the reason that having read the foregoing description of the form and arrangement of the several parts of the machine, of the drawings and their mode of operation, and the description 95 of their correlative operation, any person of average skill in the art can readily develop said cam paths, grooves, and surfaces without the exercise of invention and with no greater skill than is possessed by the average 100 skilled mechanic.

While I have described herein the preferred form of my invention, it is to be understood that my invention, in its broadest aspect, is susceptible of embodiment in various forms 105 of mechanism. While I consider it preferable to employ two stitch setting or pricking-up tools operating upon opposite sides of the stitch to compress and set it, I consider that my invention may be embodied in a machine 110 employing but one stitch setting or pricking-up tool coöperating with the stitch-forming mechanism to engage and compress a stitch and to release the pressure upon the stitch while the stitch-forming mechanism makes a 115 further pull upon the thread to further tighten the stitch around the compressed leather or materials. While I consider that the illustrated embodiment of my invention contemplating the use of two stitch setting or pricking-up tools operating upon opposite sides of the stitch to feed the work after the complete formation of the stitch is the best construction, because each sustains the pressure 120 of the other, I consider that my invention is 125 susceptible of embodiment in a machine in which one stitch setting or pricking-up tool is employed which engages a stitch after it has been formed by the stitch-forming mechanism and compresses and shapes it, and it 130 thereafter feeds the work the desired length for the next stitch. Furthermore, in case my invention was embodied in a machine for forming a chain-stitch by the use of a

hooked needle it is obvious that one stitch setting or pricking-up tool can be employed in connection therewith, operating upon the single-thread side of the seam to shape and 5 form the crowns of the stitches. My invention is not limited to a straight eye-pointed needle, but may be embodied in a straight or curved hooked needle sewing - machine whether of the chain-stitch or the lock-stitch 10 type and with either one or two stitch setting or pricking-up tools, as may be desired. I may employ any suitable stitch setting or pricking-up tool or tools, as my invention is not limited to any particular form of such 15 tool. In so far as I am advised of the state of the art, I am the first to make a sewing-machine embodying stitch-forming mechanism and stitch setting or pricking-up devices in which after the stitch is formed and after 20 the application to the stitch of the stitch setting or pricking-up tools a further pull is exerted upon the thread by the stitch-forming mechanism. I am the first, so far as I am aware, to make a sewing-machine of the above 25 type in which the work is fed by the stitch setting or pricking-up devices. I am the first, so far as I am aware, to make a machine of the above type in which the stitch setting or pricking-up devices operate more than once 30 upon the stitch to shape and compress it to the desired form, and I am the first, so far as I am aware, to make a sewing-machine of the above type in which the stitch setting or pricking-up devices operate twice upon the 35 stitch to shape and conform it to the desired form with an interval between the applications of such pressures during which the stitch-forming mechanism operates to make a further pull upon the thread to tighten the 40 stitch around the material.

It is to be noted that in a machine embodying the present invention the stitch-forming mechanism first forms or produces the concatenation of thread, which is known as a "stitch," 45 without bringing the stitch to its final or completed shape and position in the materials. This operation, through this specification and claims, I have uniformly described as the "stitch-forming" operation. I have used the 50 expression "stitch setting or pricking-up devices" to describe the tools which engage and shape the stitch after it has been formed and before the stitch is tightened to its final position in the materials. I have used the expression "to set or prick up the stitch" to describe the operation performed by the stitch setting or pricking-up devices.

Having thus described my invention, I claim as new and desire to secure by Letters 60 Patent of the United States—

1. A sewing and pricking-up machine, having, in combination, stitche-forming mechanism, a stitch setting or pricking-up tool, the stitch-forming mechanism acting to form a 65 stitch and to exert a further pull on the thread of the just-formed stitch after the operation thereon of the stitch setting or prick-

ing-up tool, and means for actuating the parts, substantially as described.

2. A sewing and pricking-up machine, having, in combination, stitch-forming mechanism, a stitch setting or pricking-up tool acting to feed the work, and means for actuating the parts, substantially as described. 70

3. A sewing and pricking-up machine, having, in combination, stitch-forming mechanism, a stitch setting or pricking-up tool acting to set or prick up a stitch and thereafter to feed the work, the stitch-forming mechanism acting to form a stitch and to exert a further 80 pull on the thread of the just-formed stitch after being set or pricked up by the stitch setting or pricking-up tool, and means for actuating the parts, substantially as described. 85

4. A sewing and pricking-up machine, having, in combination, stitch-forming mechanism, a stitch setting or pricking-up tool, acting to set or prick up a stitch and to withdraw therefrom, the stitch-forming mechanism acting to form a stitch and to exert a further pull on the thread after the withdrawal of the stitch setting or pricking-up tool, and means for actuating the parts, substantially as described. 90

5. A sewing and pricking-up machine, having, in combination, stitch-forming mechanism, a stitch setting or pricking-up tool acting to set or prick up a stitch, to withdraw therefrom, and again to engage the stitch and feed the work, and means for actuating the parts, substantially as described. 95

6. A sewing and pricking-up machine, having, in combination, a stitch setting or pricking-up tool acting to set or prick up a stitch to withdraw therefrom and again to engage the stitch and feed the work, the stitch-forming mechanism acting to form a stitch and to exert a further pull on the thread of the just-formed stitch while the stitch setting or pricking-up tool is withdrawn from the work, and means for actuating the parts, substantially as described. 105

7. A sewing and pricking-up machine having, in combination, stitch-forming mechanism, two stitche setting or pricking-up tools operating upon opposite sides of a stitch, the stitch-forming mechanism acting to form a stitch and to exert a further pull on the thread of the just-formed stitch after the operation 110 thereon of the stitch setting or pricking-up tools, and means for actuating the parts, substantially as described. 120

8. A sewing and pricking-up machine, having, in combination, stitche-forming mechanism, two stitch setting or pricking-up tools operating on opposite sides of a stitch and acting to feed the work, and means for actuating the parts, substantially as described. 125

9. A sewing and pricking-up machine, having, in combination, stitche-forming mechanism, two stitch setting or pricking-up tools operating on opposite sides of a stitch to set or prick it up and thereafter to feed the work, 130

the stitch-forming mechanism acting to form a stitch and to exert a further pull on the thread of the just-formed stitch after being set or pricked up by the stitch setting or 5 pricking-up tools, and means for actuating the parts, substantially as described.

10. A sewing and pricking-up machine, having, in combination, stitch-forming mechanism, two stitch setting or pricking-up tools 10 operating on opposite sides of a stitch, acting to set or prick up a stitch and to withdraw therefrom, the stitch-forming mechanism acting to form a stitch and to exert a further pull on the thread after the withdrawal 15 of the stitch setting or pricking-up tools, and means for actuating the parts, substantially as described.

11. A sewing and pricking-up machine, having, in combination, stitch-forming mechanism, two stitch setting or pricking-up tools 20 acting to set or prick up the opposite sides of a stitch to withdraw therefrom and again to engage the stitch and feed the work, and means for actuating the parts, substantially 25 as described.

12. A sewing and pricking-up machine, having, in combination, stitch-forming mechanism, two stitch setting or pricking-up tools operating on opposite sides of a stitch to set 30 or prick up the stitch, to withdraw therefrom and again to engage the stitch and feed the work, the stitch-forming mechanism acting to form a stitch and to exert a further pull on the thread of the just-formed stitch 35 while the stitch setting or pricking-up tools are withdrawn from the stitch, and means for actuating the parts, substantially as described.

13. A sewing and pricking-up machine, having, in combination, stitch-forming mechanism comprising a take-up, a stitch setting or 40 pricking-up tool, the stitch-forming mechanism acting to form a stitch and the take-up acting to exert a further pull on the thread 45 of the just-formed stitch after the operation thereon of the stitch setting or pricking-up tool, and means for actuating the parts, substantially as described.

14. A sewing and pricking-up machine, having, in combination, stitch-forming mechanism, comprising a take-up, two stitch setting or 50 pricking-up tools operating on opposite sides of a stitch, the stitch-forming mechanism acting to form a stitch and the take-up 55 acting to exert a further pull on the thread of the just-formed stitch after the operation thereon of the stitch setting or pricking-up tools, and means for actuating the parts, substantially as described.

60 15. A lock-stitch-sewing and pricking-up machine, having, in combination, a needle, a shuttle, a take-up, a stitch setting or pricking-up tool, the needle, shuttle and take-up acting to form a stitch and to exert a further 65 pull on the thread of the just-formed stitch after the operation thereon of the stitch set-

ting or pricking-up tool, and means for actuating the parts, substantially as described.

16. A lock-stitch-sewing and pricking-up machine, having, in combination, a needle, a 70 shuttle, a take-up, two stitch setting or pricking-up tools operating on opposite sides of a stitch, the needle, shuttle and take-up acting to form a stitch and to exert a further pull on the thread of the just-formed stitch after the 75 operation thereon of the stitch setting or pricking-up tools, and means for actuating the parts, substantially as described.

17. A sewing and pricking-up machine, having, in combination, stitch-forming mechanism, two stitch setting or pricking-up tools 80 for setting or pricking up the opposite sides of a stitch, and mechanism for simultaneously moving the tools to feed the work, substantially as described. 85

18. A sewing and pricking-up machine, having, in combination, stitch-forming mechanism, two stitch setting or pricking-up tools for setting or pricking up the opposite sides of a stitch, mechanism for simultaneously advancing the tools to set or prick up a stitch and mechanism for simultaneously moving the tools laterally to feed the work, substantially as described. 90

19. A sewing and pricking-up machine, having, in combination, stitch-forming mechanism, two stitch setting or pricking-up tools for setting or pricking up the opposite sides of a stitch, two slides upon which such tools are mounted, and mechanism for moving the 100 slides simultaneously to feed the work, substantially as described. 95

20. A sewing and pricking-up machine, having, in combination, stitch-forming mechanism, a stitch setting or pricking-up tool acting to feed the work, a feed-adjuster, and means for actuating the parts, substantially 105 as described.

21. A sewing and pricking-up machine, having, in combination, stitch-forming mechanism, two stitch setting or pricking-up tools for setting or pricking up the opposite sides of a stitch, two slides upon which such tools are mounted, a slide-actuating device having an arm, a rock-shaft having an arm provided 110 with an adjustable slot adapted to engage the arm on the slide-actuating device, and means for oscillating the rock-shaft, substantially as described. 115

22. A sewing and pricking-up machine, having, in combination, stitch-forming mechanism, a stitch setting or pricking-up tool acting to feed the work, a slide upon which the stitch setting or pricking-up tool is mounted, a slide-actuating device having an arm, a rock-shaft 120 having an arm provided with an adjustable slot adapted to engage the arm on the slide-actuating device, and means for oscillating the rock-shaft, substantially as described. 125

23. The combination with a stitch setting 130 or pricking-up tool acting to set or prick up the stitches of a seam and to feed the work,

of a presser acting to release the work during the feed, and means for actuating the parts, substantially as described.

24. The combination with two stitch setting or pricking-up tools operating on opposite sides of a stitch, of means for actuating the tools to set or prick up a stitch, and to feed the work, substantially as described.

25. The combination with two stitch setting or pricking-up tools operating on opposite sides of a stitch, of means for actuating the tools to set or prick up a stitch and to feed the work, and a presser to hold the work, substantially as described.

26. The combination with two stitch setting or pricking-up tools operating on opposite sides of a stitch, of means for actuating the tools to set or prick up a stitch and to feed the work, a presser to hold the work at all times except during the feed, and means for actuating the presser, substantially as described.

27. A sewing and pricking-up machine, having, in combination, stitch-forming mechanism, a stitch setting or pricking-up tool, the stitch-forming mechanism acting to form a stitch and to exert a further pull on the thread after the setting or pricking up of the stitch, and the stitch setting or pricking-up tool acting to hold the tightened stitch until after the next stitch is formed, and means for actuating the parts, substantially as described.

28. A sewing and pricking-up machine, having, in combination, stitch-forming mechanism, two stitch setting or pricking-up tools operating on opposite sides of a stitch, the stitch-forming mechanism acting to form a

stitch and to exert a further pull on the thread after the setting or pricking up of the stitch, and the stitch setting or pricking-up tools acting to hold the tightened stitch until after the next stitch is formed, and means for actuating the parts, substantially as described.

29. A sewing or pricking-up machine, having, in combination, stitch-forming mechanism, a stitch setting or pricking-up tool, acting to set or prick up a stitch and to feed the work, the stitch-forming mechanism acting to form a stitch and to exert a further pull on the thread after the pricking-up operation and before the feed, the stitch setting or pricking-up tool acting to hold the tightened stitch after the feed until the next stitch is formed, substantially as described.

30. A sewing or pricking-up machine, having, in combination, stitch-forming mechanism, two stitch setting or pricking-up tools operating on opposite sides of the work, acting to set or prick up a stitch and to feed the work, the stitch-forming mechanism acting to form a stitch and to exert a further pull on the thread after the pricking-up operation and before the feed, the stitch setting or pricking-up tools acting to hold the tightened stitch after the feed until the next stitch is formed, substantially as described.

In testimony whereof I affix my signature in presence of two witnesses.

MARSHALL HENRY PEARSON.
